UNITED STATES PATENT OFFICE.

ELIAS P. JOSLYN, OF BROCKPORT, NEW YORK.

FIFTH-WHEEL FOR VEHICLES.

SPECIFICATION forming part of Letters Patent No. 244,996, dated August 2, 1881.

Application filed June 17, 1881. (No model.)

To all whom it may concern:

Be it known that I, ELIAS P. JOSLYN, of Brockport, in the county of Monroe and State of New York, have invented a new and useful Improvement in Fifth-Wheels for Vehicles, which improvement is fully set forth in the following specification and accompanying drawings.

The object of my invention is to produce a fifth-wheel for road-vehicles that shall work easily and noiselessly under a loaded axle, the forward parts of the circular bearing-plates being held together by a yielding pressure and the king-bolt passing through three concentric hemispherical or cup-shaped bearing-surfaces arranged one within another for the purpose of perfectly centering the swinging action of the axle under the spring bar or bolster.

Referring to the drawings, Figure 1 represents a plan of my invention; Fig. 2, a vertical section taken centrally along the reach, view indicated by the arrow in Fig. 1; and Fig. 3, a detached view, drawn to a larger scale, showing more clearly the clamp at the front parts of the bearing-plates, view indicated by the arrow in Fig. 2.

In the figures, A is a reach, B an axle, C the stock clipped to said axle, and D a spring-bar attached to the reach, all of ordinary construction. d is a metallic plate attached to the under surface of the spring-bar D, and b a corresponding plate attached to the stock C, the front edges of said plates being circular and concentric with the king-bolt f.

The plate d, at a point in rear of the spring-bar, is formed into a hemispherical shell, a, convexed upward; and the plate b at the same point is provided with a corresponding shell, c, fitting perfectly within the shell a, as shown.

The under strap or brace, g, bolted to the under side of the reach, is provided with a hemispherical upward projection, e, which fits within the concavity of the shell c, and a king-bolt, f, of ordinary construction, passes vertically down through the said parts a, c, and e, concentrically therewith, having a lock-nut, h, beneath the brace g, as shown.

The plate d, at its front edge, has a part projecting over the plate b, which enters down-

ward, thence horizontally backward under said plate b, thence vertically upward, forming a hook-shaped part, F. Within this hook is placed a gib, k, which is held against the under surface of the plate b by a set-screw, l, passing up through the lower horizontal part 55 of the hook. The end of the set-screw presses directly against a metallic plate, o, within the hook, between which plate and the gib k is inserted an india-rubber block or cushion, n. By this means the gib k is held against the 60 plate b by a slightly-yielding pressure. As the axle is turned under the spring-bar by being cramped one way or the other, for the purpose of changing the course of the vehicle, the plate b slides around between the gib k and superincumbent plate d. The cushion n beneath the gib causes the plate b to work more smoothly between said gib and plate d, and with less friction and noise. When the axle is swung around beneath the spring-bar D, as above described, the hemisphere c turns between the hemispherical shell a and the hemisphere e. This arrangement of parts perfectly centers the swinging motion of the axle, and the king-bolt is not subjected to detraction or a shearing strain, this being prevented by the fitting together of the hemispheres, as above described.

The lock-nut h is the same as that shown and described in the patent granted to me April 13, 1880, and numbered 226,452; and it consists of a square hollow shell, h, containing within the rectangular cavity a yielding substance, s, and a screw-nut proper, p, for the king-bolt. The nut p, as described in the patent above mentioned, having its edges fitted to the corresponding inner surfaces of the shell h, turns with said shell as the latter is turned in the usual manner by an ordinary wrench. When the shell h is turned in such a manner as to carry the nut p onto the bolt, the part s becomes compressed between the nut and the bottom of the shell. If the part s is of a substance similar in nature to india-rubber, its compression beneath the nut p will cause it to pinch tightly the bolt f, and thus form a lock for the nut p and shell. Its elasticity also causes the shell h to remain at all times in contact with the strap g, which prevents any rattling of the parts.

By placing the center of the swinging motion of the axle in rear of the spring-bar the vehicle is much more quickly and easily turned. This feature alone by itself, however, I do not claim as new.

I claim as my invention—

1. In combination with the axle stock C and spring-bar D of a wagon, the plates b and d, the latter being provided with a hook-shaped part, F, containing a gib, k, plate o, and cushion n, and a set-screw, l, substantially as shown.
2. In combination with the axle C, spring-bar D, and reach A, the plates b and d, and

the brace g, the plate d being provided with a hook-shaped part, F, gib k, and screw l, said plates and brace being formed respectively into hemispheres a, c, and e, as shown.

3. The plates d and b of a fifth-wheel of a vehicle, formed into mutually bearing hemispheres a and c at a point in rear of the axle, and held together by a gib and screw at a point in front of the axle, substantially as shown.

E. P. JOSLYN.
